UNITED STATES PATENT OFFICE.

JOSEPH KEPPLER, OF NEW YORK, N. Y., ASSIGNOR TO BENJAMIN T. B. HYDE,
OF NEW YORK, N. Y., TRADING AS HYDE EXPLORING EXPEDITION.

DESIGN FOR AN UPRIGHT OR SUPPORT FOR FURNITURE.

SPECIFICATION forming part of Design No. 36,252, dated March 24, 1903.

Application filed February 24, 1903. Serial No. 144,924. Term of patent 7 years.

To all whom it may concern:

Be it known that I, JOSEPH KEPPLER, a citizen of the United States, residing at the city of New York, in the county and State of New York, have invented and produced a new, original, and ornamental Design for Uprights or Supports for Furniture, of which the following is a specification, reference being had to the accompanying drawing, forming part hereof, and in which an upright or support showing my design is illustrated in a perspective view.

As shown in the drawing, the leading or material feature of my design consists in the shape or configuration of the upright or support combined with the surface ornamentation thereof.

As illustrated, the upright or support has an upper horizontal member *a*, which in its upper outline is of zigzag shape, a lower member or base *b*, and an intermediate member or body *d*. The surface of the member *a* is ornamented with zigzag lines to represent in Indian mythology clouds. It also has a central ornament *d'* to represent in Indian mythology the head of an eagle. The base *b* has intermediate of its sides a part *d*² of a shape or configuration corresponding con-

ventionally to the tail, the side parts *b'* representing the claws of the mythological eagle. 30 The body *d* has a central portion *d*³, representing the body of the eagle, and two curved portions *d*⁴, one on either side of the central portion *d*³ and representing conventionally the wings of the eagle. On the surface of 35 the central portion *d*³ and the wing portions *d*⁴ of the body *d* are various ornamentations representing symbolically the attributes of the eagle, according to Indian mythology.

When viewed in front elevation, the design represents conventionally a horizontal panel *a*, representing the clouds supported by the head and wings of an eagle.

Having thus described my invention, what I claim as new, and desire to secure by Letters 45 Patent, is—

The ornamental design for an upright or support for furniture, substantially as herein shown and described.

In testimony whereof I have hereunto set 50 my signature in the presence of two subscribing witnesses.

JOS. KEPPLER.
